UNITED STATES PATENT OFFICE.

ANTOINE EMILE VÉZINA, OF OUTREMONT, QUEBEC, CANADA.

MEANS FOR REVOLVING FIRE-BOX DOORS.

1,197,411.

Specification of Letters Patent. Patented Sept. 5, 1916.

Application filed October 29, 1915. Serial No. 58,691.

To all whom it may concern:

Be it known that I, ANTOINE EMILE VÉZINA, a subject of the King of Great Britain, and resident in Outremont, in the Province of Quebec, in the Dominion of Canada, have invented certain new and useful Improvements in Means for Revolving Fire-Box Doors; and I do hereby declare that the following is a full, clear, and exact description 10 of the same.

The invention relates to means for revolving fire box doors of the kind described in applicant's Canadian Patent No. 152,768, and dated December 23rd, 1913, and consists 15 of a lever connected at one end to a quadrant which is in engagement with a pinion mounted on the actuating shaft of the doors, said lever being fulcrumed intermediate of its length and a foot pedal pivotally secured 20 in the floor, disposed over the other end of said lever and means to actuate said lever so that by pressing the foot pedal downwardly, it will cause the revolving doors to be opened and by releasing said foot pedal, 25 the doors will be brought back into their closed position by means of a spring secured to one side of the quadrant, at one end, and to the boiler plate at the other end.

The object of the invention is to provide 30 a means to actuate the revolving doors without causing any strain on the operator also whereby a certain amount of play will be given the said foot pedal for vibration, which usually happens on locomotives and 35 whereby the doors will be kept opened even if the operator's foot did temporarily leave the pedal. The trouble with the ordinary foot pedals used for revolving fire box doors lies in the fact that vibration often causes 40 the foot to slip off, or lift from the pedal and immediately the doors close. Applicant's pedal is so constructed that it would avoid also these inconveniences.

The invention will be hereinafter described with the aid of the accompanying drawings in which—

Figure 1 is a side elevation of the invention showing a portion of the door operating shaft and pedal, the said pedal being in its 50 non-operative position. Fig. 2 is a side elevation of the invention, the foot pedal being shown in its operative position. Fig. 3 is a top view of the foot pedal and Fig. 4 is an under view of the foot pedal.

Like numerals of reference indicate corresponding parts in each figure.

Referring to the drawings, 1 indicates the front plate of a locomotive boiler and 2 represents the floor in which is secured the rectangular frame 4 which is secured to the 60 said floor by means of the projecting ears 5 and bolts 6.

7 is a foot pedal pivotally mounted at one end on the shafts 8, which are secured in the frame 4. The other end of said pedal being 65 provided with slots 9 and 10.

11 is a shaft mounted in the sides of said pedal and journaled therein and provided with a roller 12, said roller contacting with one end of the lever 13, which is fulcrumed 70 at 14.

15 is a rod having a forked end 16 to which is pivotally connected the other end of the lever 13, said rod passing through a slot in the floor 2 and being inclosed up to 75 a certain height by a casing 17, to prevent cinders, or coal from dropping beneath the floor.

18 is a fork connection to which is threaded the rod 15 at one end and 19 is a crank arm secured on the shaft 20 at one end and pivotally secured at the other end between the forks 21 on connection 18.

22 is a quadrant rigidly mounted on the shaft 20 and 23 is a pinion engaging said 85 quadrant.

24 is a spiral spring secured at one end to one side of the quadrant and at the other end to a hook 25 which is secured on a portion of the boiler. A number of hooks have 90 been provided in order that if it is necessary to give more tension to the said spring 24, it may be attached to another hook disposed under said hook 25.

26 is an arm mounted on the shaft 11 95 within the foot pedal casing and having at one end the notch 27, which slightly projects through the slot 9 and is adapted to engage the pawl 28 pivotally mounted on the lugs 29 when the foot pedal is pressed downwardly, the other end of said arm 26 extending through the slot 10 and terminating in the expanded head 30.

It is readily seen that in the operation of the invention herein described, the foot 105 pedal 7 is pressed with the foot downwardly in the position shown in Fig. 2. By pressing down said foot pedal 7 the fulcrumed lever 13 will be pressed downwardly by the roller 12 and the quadrant 22 will be actuated. In 110 pressing down the foot pedal 7, the pawl 28 is adapted to engage the notch 27 in the end

of the arm 26. Therefore, should the foot of the operator lift from contact with the pedal, due to vibration, the revolving doors will not close until the arm 26 has followed 5 its course to the position shown in dotted lines in Fig. 2. The arm 26 having followed the above mentioned course, the pawl 28 will disengage from the notch 27 and the foot 10 pedal will immediately come into its inoperative position. It may here be stated that the sides of the frame 4 are beveled in order that if any cinders, dust, or snow should fall between the sides of the foot pedal 7 and the frame it will not block, or clog-up. 15 It must be understood that the constructional details of the herein described invention can be modified, if found desirable, so long as I do not depart from the invention as claimed in the following claims for 20 novelty.

What I claim is:—

1. Means for revolving fire box doors, comprising a lever fulcrumed intermediate of its length, one end of said lever being 25 connected to a quadrant which actuates the fire box doors, an opening provided in the floor, a frame secured in said opening, a foot pedal pivotally secured in said frame, one end of said foot pedal forming a casing, a 30 slot in the end of said casing, a slot through the top part of said casing, a shaft within said casing and journaled in its sides, a roller mounted on said shaft and resting on the other end of said lever, an arm mounted 35 on said shaft projecting through the slot provided in the top of said casing and a notch provided at the other end of said arm, a pawl secured in said frame, coacting with 40 said notch and means to adjust the movement of said fulcrumed lever substantially as described.

2. Means for revolving fire box doors, comprising a lever fulcrumed intermediate of its length, a quadrant actuating the fire 45 box doors, said quadrant being mounted on a shaft, a crank arm rigidly mounted on said shaft and a rod connecting said crank arm to one end of said lever, an opening provided in the floor, a frame secured in said

opening, a foot pedal pivotally secured in 50 said frame, one end of said foot pedal forming a casing, a slot in the end of said casing, a slot through the top part of said casing, a shaft within said casing and journaled in 55 its sides, a roller mounted on said shaft and resting on the other end of said lever, an arm mounted on said shaft projecting through the slot provided in the top of said casing and a notch provided at the other end of said arm, a pawl secured in said frame, 60 coacting with said notch and means to adjust the throw of said fulcrumed lever substantially as described.

3. Means for revolving fire box doors, comprising a lever fulcrumed intermediate 65 of its length, a quadrant actuating the fire box doors, said quadrant being mounted on a shaft, a crank arm rigidly mounted on said shaft, a rod pivotally connecting the crank arm to one end of said lever, a spring secured at one end of said quadrant, and at the other end to the face plate of the boiler, an opening provided in the floor, a frame secured in said opening, the inner sides of 70 which are beveled, a foot pedal suitably pivoted in said frame, one end of said foot pedal being embossed and forming a casing, a slot in the end of said casing, a slot through the top of said casing, a shaft journaled in the lowermost sides of said casing, 75 a roller mounted on said shaft resting on the other end of said lever, an arm pivotally mounted on said shaft, said arm being curved intermediate of its length and projecting through the slot on top of said casing, 80 a boss on the upper end of said arm in order to stop its downward movement, a notch provided at the other end of said arm, a pawl pivotally secured in lugs projecting 85 from said frame and coacting with, said notch and means to adjust the throw of said 90 fulcrumed lever substantially as described.

Signed at Montreal, Quebec, Canada, this 2nd. day of October, 1915.

ANTOINE EMILE VÉZINA.
